(57) **CLAIM**

The ornamental design for holder for cell phone and other articles, as shown and described.

DESCRIPTION

FIG. 1 is a perspective view of holder for cell phone and other articles showing my design which includes an insert and an outer portion containing the insert;

FIG. 2 is a top plan view thereof;

FIG. 3 is a left side elevation view thereof, the right side elevation view being a mirror image;

FIG. 4 is a front elevation view thereof;

FIG. 5 is a rear elevation view thereof; and,

FIG. 6 is a bottom plan view thereof.

The broken line showing of a cell phone and other articles in FIG. 1 of the drawing is for illustrative purposes only and forms no part of the claimed design.
